WASHING APPARATUS

John J. Meehan, Washington, D. C., assignor of
one-half to Douglas P. Clark, Washington,
D. C.

Application June 23, 1934, Serial No. 732,153

2 Claims. (Cl. 299—59)

My invention relates to washing apparatus and more specifically to apparatus for washing type in type forms.

The principal object of my invention is to provide apparatus whereby type forms mounted on a conveying means are caused to be moved past nozzles spraying a cleansing fluid over the forms so that the type is thoroughly cleansed.

The art of cleaning type is as old as the art of printing. For many years and until comparatively recently type was cleaned by hand devices. As the art grew various devices such as brushes or sponges were attached to the press so that the type was cleaned while still on the press. In my invention, I mount the type form on a conveyor and move it past spraying nozzles. It is, of course, old in other cleaning arts to mount the object to be cleaned on a conveyor and thus move it relative to the cleaning sprays or brushes. This method is used for cleaning automobiles, batteries, dishes, railroad cars, etc. It is therefore not the purpose of my invention to cover such cleaning systems broadly.

So far as I am aware, however, the combination of a spraying nozzle and a conveyor has not been used for cleaning type forms and for a very unobvious reason. For generations it has been the habit and custom of printers to fill in one side and one end of type forms with "spit balls" or paper wads in order to give the type a tight fit in the form. During the cleaning process these wads or "spit balls" accompanied by the ink and pulp fragments from the paper mix with the cleansing medium and thus tend to clog up the spray nozzles. This same problem exists on a smaller scale in the paper pulp cleaning industry. In that industry much pulp tends to get mixed up with the cleansing solution but the particles are smaller and will thus pass through ordinary spray nozzles. The types of nozzles used in ordinary cleaning methods have been tried in type cleaning processes and have been found unsatisfactory, for reasons indicated above and which will be more fully explained below.

It is, therefore, another object of my invention to provide a novel type of spray nozzle that will not be clogged up with paper wads when used to clean type in the forms.

It is a further object of my invention to provide a slide arrangement whereby my novel type of spray nozzle may be cleaned.

It is a further object of my invention to provide means whereby the cleansing solution does not come in contact with the solution used for rinsing thus saving the former from dilution.

Still another object of my invention is to provide a means to effectively preheat the cleansing solution so that the ink on the type is more readily dissolved.

Other objects of my invention, some of them more or less ancillary or incidental to those above mentioned, will appear hereinafter as the description proceeds.

In the drawings:

Figure 1 is an elevation view, partly in cross section, of a typical form of type cleaning apparatus embodying my invention. 10

Figure 2 is a side view of the flexible barrier along line 2—2 of Figure 1.

Figure 3 is a plan sectional view of the apparatus shown in Figure 1, taken along line 3—3 of that figure. 15

Figure 4 is an enlarged horizontal section of the nozzle taken along line 4—4 of Figure 1.

Figure 5 is a horizontal section of the nozzle of 20 Figure 4 taken through the improved cleaning means for the nozzle, and

Figures 6 and 7 are variations of Figure 5.

Referring more particularly to the drawings, 10 represents a form containing type which is mounted on the conveyor 11. Briefly, my type cleaning apparatus comprises the conveyor 11, cleansing nozzles 12, supply means for the cleansing solution, rinsing nozzles 13, supply means for the rinsing solution, a flexible barrier or door 14 to prevent the two solutions from intermingling, and return means for the two solutions. 25

The cleansing solution is kept in any suitable container such as the tank 15. Any good cleansing solution can be used but I prefer to use sodium silicate (Na_2SiO_3). It is to be understood that my invention is not directed towards nor is it limited to the use of any particular kind of cleansing fluid. Inside the tank may be provided any convenient heating means such as the steam coil 16 to preheat the cleansing solution so that the ink on the type form may be more readily dissolved. The cleansing solution is pumped through pipes 17 and 18 by a pump (not shown) to the nozzles 12. 35

The nozzles 12 are shown by me as vertically disposed but it is understood by those skilled in the art that they could be horizontally or angularly disposed and still be within the scope of my invention. Running almost the entire length of the nozzle pipes 12 are axially extending slots 19 which slots are wider at the inner diameter of the pipes than at the outer diameter for a purpose to be hereinafter more fully described. I am aware that nozzles containing long axial slots 40

have been used heretofore to clean railroad cars. Such a nozzle is shown in Letters Patent No. 894,919 issued on Aug. 4, 1908 to Harrison M. Turner. However, the slot in the Turner nozzle 5 has the same width on both inner and outer diameters of the pipe and there is no provision for cleaning the slot. As will be explained more fully below these differences are important ones and make for the success of my improved nozzle 10 in the type cleaning art. Projecting into the pipes 12 from the top and extending the whole distance of the slots are the rods 21 which carry at their lower extremities the cleaning wedges 22 which fit into the slots 19 and which can be moved up and down in the slots to clean them. 15 This movement may be accomplished by any suitable means but I have shown the rods 21 terminating into heads 22 by means of which the rods 21 and thus the cleaning wedges 22 may be conveniently raised and lowered thus scraping out all 20 paper wads, pulp, dirt, etc. As there is a close fit between the cleaning member and the edges of the slot, all pulp, ink, etc. can be thoroughly scraped off the edges of the slot. It is obvious to 25 those skilled in the art that this nozzle cleaning operation may be performed without halting or delaying the cleansing process. At the top of each nozzle pipe and around the rods 21 are packing chambers 23 to prevent water leaking 30 out at the top.

In Figures 5, 6 and 7, I have shown various types of slot openings together with their accompanying cleaners. Fig. 5 shows a wedge type. This produces a more concentrated spray and at 35 the same time prevents the spit-balls or paper wads mentioned above from clogging the slot. As can be seen the opening on the inner circumference 24 is larger than on the outer circumference 25. This allows a forceful, concentrated 40 spray. The cleaning device or wedge 20 is attached to the rod 21 in each case near the bottom of the rod as by means of a rod 26 which may be a part of rod 21. Figures 6 and 7 are variations which have been found to be very successful as 45 they eliminate all sharp corners such as 27 and 28 of Figure 4 which would tend to impede the progress of the cleansing medium through the slot. These sharp corners have been found to 50 delay the progress of spit balls and thus they pile up and stop up the passage. If they are not given an opportunity to pile up it has been found that they pass out through the slot with no difficulty.

Referring again to Figures 1, 2 and 3, I have 55 shown the apparatus as divided into cleansing compartment 29 and a rinsing compartment 30. These compartments are bounded by partition members 31 and 32, top member 33, and flexible barriers 14. These flexible barriers (see Figure 60 2) have openings 34 for the conveyor to pass through and slits 35 extending nearly their whole height to permit the passage of the type form. A smaller opening 36 appears at the top of each barrier which is to permit the portions of the 65 barrier on each side of the slit 35 to give when the type form comes against it, thus allowing the type form to pass therethrough. In Figure 1, I have shown the type form 18 just passing through the flexible barrier 14 on the right of the figure, thus entering the cleaning compartment 29. The 70 flexible barriers 14 may be of any suitable material such as rubber or cloth. It is readily apparent to those skilled in the art that my flexible barriers 14 permit the passage of the type form 75 along the length of the conveyor but nevertheless

keep the fluids within the bounds of their respective compartments.

In the rinsing compartment, which sometimes is unnecessary, I have shown two nozzles 13 which may or may not be similar to those already described for the cleansing operation. As the spit balls, wads, pulp and ink have mostly been removed and as the fluids are restrained from intermingling, it may not be necessary to use for the rinsing operation the specific type of nozzle 10 described by me as desirable for the cleansing operation. Any form of nozzle might be used, depending on the local conditions. For convenience, I have shown the nozzles 13 as being similar to the nozzles 12 and having the same 15 cleaning means therefor. As a rinsing fluid I preferably use plain water which may be pre-heated, if desired, by any convenient means.

It will thus be seen that I have described a practical and efficient apparatus for cleaning type 20 forms. The type form is placed on the conveyor at the right end and guided by guide rails 31. The conveyor, driven by any convenient means (not shown) moves the type form into the cleansing compartment 29 where it is 25 sprayed by the cleansing solution from the nozzles 12. The solution is placed under pressure so that the concentrated spray drives out the pulp, paper wads, ink etc. from the type form. As the system is a circulatory one, this matter would 30 eventually clog up the spray nozzles, if it were not for the cleaning means 28 which I have provided for this purpose. The wedge-like members 28 keep the slot in the nozzle free from surplus matter at all times and they may be 35 easily operated during the cleansing operation by merely lifting the rods 21 and letting them drop down the slots thus cleaning them. The cleansing solution and the surplus matter are partially separated by a screen 38 which prevents the 40 larger particles of material from passing through to the sump 39. There is a pipe 40 leading to the cleansing solution tank 15 from the sump 39. At convenient points in the circulatory 45 cleansing solution system I have placed valves 41.

After passing through the cleansing compartment, the type form passes through the middle flexible barrier 14 and into the rinsing compartment. As mentioned above, this compartment may in some instances be omitted, but generally it has been found desirable in order to thoroughly rinse the type. Because of the fact that sometimes wads of paper may be carried over into the rinsing compartment by the type form, I have shown the nozzles 13 as of the same type 55 as the cleansing nozzles 12 with the same provisions for cleaning them. This compartment has a screen 42 to prevent large particles of matter from going into the sump 43 which leads to a convenient outlet, as a sewer (not shown) by 60 means of pipes 44. The inlet to the nozzles 13 is by means of pipes 45 which are preferably connected to a source of water supply which preferably is under pressure. It will thus be evident that I have kept the solutions in the two compartments 65 29 and 30 from intermingling by means of the flexible middle barrier 14 and the separate screens and sums for the two compartments. This thus prevents dilution of the cleansing solution.

After the rinsing operation the type form passes 70 through the left flexible barrier 14 where it may be removed.

My invention is not limited in its application to the particular construction or constructions herein illustrated, as various changes might be 75

made in the construction or constructions shown without departing from the spirit of my invention as set forth in the appended claims.

I claim:

- 5 1. A nozzle for cleaning type comprising a source of supply of cleaning fluid, a pipe, a longitudinal slot of uniform cross-section throughout its length in said pipe, said slot being larger on the inner circumference of said pipe than on the outer, a packing chamber at the end of said nozzle remote from said source of supply, a rod passing through said packing chamber and extending into the interior of said pipe, and a scraping member attached to said rod and adapted to move in said longitudinal opening, said scraping member being characterized in that its edges are parallel to the side walls of the slot and are adapted to closely fit and simultaneously scrape said side walls.
- 10 2. A nozzle for cleaning type comprising a source of supply of cleaning fluid, a pipe, a longitudinal slot of uniform cross-section throughout its length in said pipe, said slot being larger on the inner circumference of said pipe than on the outer and presenting rounded corners to the flow of liquid through said slot, a packing chamber at the end of said nozzle remote from said source of supply, a rod passing through said packing chamber and extending into the exterior of 10 said pipe, and a scraping member attached to said pipe, and a scraping member attached to said rod and adapted to move in said longitudinal opening, said scraping member being characterized in that its edges are parallel to the side walls of the slot and are adapted to closely fit and si- 15 simultaneously scrape said side walls.

JOHN J. MEEHAN.
